United States Patent Office.

OLIVER E. PILLARD, OF NEW BRITAIN, CONNECTICUT, ASSIGNOR TO FREDERIC H. NORTH, OF SAME PLACE.

Letters Patent No. 79,388, dated June 30, 1868.

IMPROVEMENT IN PERMUTATION-LOCKS.

The Schedule referred to in these Letters Patent and making part of the same.

TO ALL WHOM IT MAY CONCERN:

Be it known that I, OLIVER E. PILLARD, of New Britain, in the county of Hartford, and State of Connecticut, have invented, made, and applied to use, a certain new and useful Improvement in Locks; and I do hereby declare the following to be a full, clear, and exact description of the said invention, reference being had to the annexed drawing, making part of this specification, wherein—

Figure 1 is an elevation of the lock, the back plate and circular tumblers being removed.

Figure 2 is a section of the lock at the spindle, and

Figure 3 is a similar section, in larger size, of the disk and ring at the end of the spindle.

Similar marks of reference denote the same parts.

The object of my invention is to prevent any indication of the position of the interior parts by a movement of the knob and spindle in any direction, and thus render it impossible to tell, by feeling, when the parts are properly placed for opening the lock.

Heretofore an inclined end to the spindle has been employed to raise the dog that acts between the tumbler and bolt, but that incline allowed of a measurement being taken of the relative position of the dog and incline, according to the extent of end motion of the spindle.

The nature of my said invention consists in an irregular circular incline or truncated cone at the end of the spindle, for raising the dog, so as to prevent reliability in the measurements of any end movement, and thus increase the difficulty in picking the lock.

And I make this truncated cone as a loose ring, that may be turned with the spindle, or be stopped by the contact therewith of the dog, while the spindle continues to be turned, and thus prevent measurements being taken at one definite point to determine the position of the dog relatively to the tumblers.

I combine, with this conical ring and dog, a ring that hangs from the dog, and prevents the spindle engaging with the bolt until the tumblers are all properly placed.

In the drawing, *a* is the lock-case, *b* the bolt, *c* the spindle *d* the index and handle, and *e* the circular tumbler to be set separately and in succession. These parts are to be of any desired character, and, being well known, do not require further description.

f is the dog on the fulcrum *g*, taking the stop *i*. On the bolt *k* is a foot to the dog *f*.

The periphery of the incline or truncated cone *n*, at the end of the spindle *c*, may be circular or undulating. I have shown the same as circular, with an undulating disk *x* between the hub *s* and ring *n*, said disk being fixed to and moving with the hub *s*. The irregular shape of the periphery of the disk *x*, as seen at the points 1 and 2, utterly deranges any effort to effect a measurement to determine any of the positions of the parts by an end motion of the spindle or otherwise, and the ring *n* will turn with the spindle when the dog is raised by one of the projections 2, and be stopped by the contact of the dog with its edge.

The incline *n*, at the end of the spindle, is not regular, being fuller on one side than on the other, as seen in larger size in fig. 3, so that if the dog is dropped by drawing the ring *n* from under the foot *k*, and the stud *o* rests upon the edges of the tumblers, any measurement of the position of that dog, by reason of the end motion allowed to said spindle to the point of contact of *n* and *k*, would be valueless in efforts to pick the lock, because of the irregularity of the cone or incline *n*; and as an additional security, the conical ring *n* is loose, so as to be stopped by the contact therewith of the foot *k*, and hence the position of the irregularities of that cone to the dial will be varied by the spindle being turned while the ring is stationary.

The bolt is moved by the teeth 3 on the hub *s* taking the teeth 4 on the bolt, but these parts cannot be brought into contact until the coinciding of the notches in the tumblers *e* allows the dog *f* to fall, and move down with it the ring *r*, that has an opening just large enough to admit said hub *s* to be drawn back into it as the teeth 3 and 4 engage together.

What I claim, and desire to secure by Letters Patent, is—

1. The incline n at the inner end of the spindle, with an irregular surface, in combination with the dog f , and series of tumblers e , as and for the purposes set forth.
2. The ring n , fitted loosely upon the inner end of the spindle, so that it may be stopped by contact with the dog f , as and for the purposes set forth.
3. The disk x , with an irregular periphery, in combination with the spindle c and incline n , substantially as and for the purposes specified.

In witness whereof, I have hereunto set my signature, this thirtieth day of November, A. D. 1867.

OLIVER E. PILLARD.
